HAIRDRESSING APPARATUS

Gertrude M. Higgins, Baltimore County, Md.

Application May 17, 1941, Serial No. 393,877

7 Claims.

(Cl. 34—90)

The invention relates to hair dressing and particularly to the drying of the hair after or as the final step of the waving and other treatments or processes in which a heated dryer is employed. Under such circumstances, i. e., during the drying step of these treatments, there is a tendency on the part of the customer to become drowsy and lose consciousness. In these instances the head droops or falls forwardly and on recovery, with the sudden return to consciousness, it is apt to bob up against the dryer with resulting bumps, or bruises and it is also notable that from weariness, inattention, or drowsiness the head is for a large portion of the drying period more or less displaced from the most efficient drying relation of the hair to the dryer.

The invention provides a support for the head which permits rest and relaxation of the neck muscles during the drying period and prevents nodding or drooping of the head and consequent bumps, bruises, and other discomforts incident to the operation of the dryer as at present employed, and which particularly prevents displacement from drying position and loss of time of the customer and of the establishment.

As hair dressing parlors and the like, where this service is performed do not, as a rule, provide sufficient attendants so that each customer is fully attended throughout the treatment, it is considered undesirable and even hazardous to use any equipment to support the head which is not so arranged that the customer can easily and instantaneously release herself from the dryer, otherwise great discomfort due to overheating may result in addition to weariness, cramping and straining of the neck muscles due to enforced and prolonged contact with the heater and/or similarly enforced retention of a single position of the head.

The object of the invention is to provide a support adapted to various makes of dryers and adjustable and otherwise adapted to the customer whereby the head is held in such relation to the dryer that the hair is maintained within the most efficient drying range without effort or muscular tension on the part of the customer and in such a way that weariness or loss of consciousness due to drowsiness or for any other reason will not cause the head to drop or droop out of proper heating and drying relation with the heater. This support is not only conveniently adjustable to the various customers but adapted to be positioned in operative relation to any dryer the operative position being yieldably maintained and the support or cushion being so arranged that the

customer can, at will, swing it aside and be instantaneously released from the dryer and thus enabled, at will, to move downwardly and/or laterally out of heating range of the dryer, complete relaxation being possible without loss of efficiency in drying and without chance of even minor injury.

In the accompanying drawing I have illustrated a dryer and dryer stand equipped with a chin support in accordance with the invention.

In the drawing:

Fig. 1 is a side elevation of the dryer, dryer stand, and the support in operative relation, the dryer stand being fragmentarily shown.

Fig. 2 is an elevation showing the support or rest and arm, also showing fragmentarily, adjacent portions of the dryer stand to which it is attached.

Fig. 3 is a top plan view of the support or rest and arm.

Fig. 4 is an elevation of the rest or support and its arm, and the adjacent portions of the stand as seen from the right in Figs. 2 and 3.

Referring to the drawing by numerals, each of which is used to indicate the same or similar parts in the different figures, the apparatus as shown, having particular reference to Fig. 1, includes an upright tubular stand 1, in which is slidably arranged a vertical rod 2, secured in adjusted position by means of a set screw 3. This sliding rod 2 is forked at its upper end at 4, carrying pivotally mounted between the arms of the fork 4 a dryer 5 which, according to the usual practice, would contain an electric heating unit not shown. The rod 2 as shown has a boss or shoulder 2^a to limit its entrance into the tubular upright 1. Fig. 1 also suggests a customer in the usual heating and drying relation to the dryer. The details of the dryer and stand are described and shown as identifying an apparatus suitable to the practice of the invention, these details are capable of wide variation forming no part of the invention.

As already pointed out, the drying operation is long and tedious and as at present practiced results in a considerable amount of discomfort due to strain and cramping of the neck and shoulder muscles incident to the attempt to maintain the head in proper relation to the dryer.

The prolonged retention of the attitude described together with the application of heat cause weariness or drowsiness with a tendency to relaxation of the muscles and drooping or nodding of the head followed by sudden awakening which has a tendency to bob the head against the dryer.

The discomfort experienced is detrimental to the good-will of the establishment patronized and the nodding of the head and sagging of the muscles due to weariness cause loss of the proper drying position and consequent loss of time.

To overcome these difficulties the invention provides a support which is most conveniently attached to the vertically sliding rod 2 and mounted for adjustment thereon. The support includes a cushion or pad 7 adapted to engage the customer beneath the chin to prevent accidental displacement. This cushion or pad 7 is mounted on a composite arm 8 which as seen in plan is U shaped to partially encircle the customer's neck to support the chin rest or pad from the dryer stand, which is necessarily at the customer's back and usually opposite the center of the back. The term "U shaped" designates concavity toward one side.

The composite arm 8 is mounted on the vertically sliding rod 2 of the stand 1 and is so arranged as to provide for accurate positioning of the pad 7 in supporting relation to the customer's chin, whereby the head is held with the hair in drying relation to the dryer 5 which, according to usual practice is concaved downwardly. As already pointed out, it is essential that the pad with the supporting arm 8 be freely movable to and from this position by and at the will of the customer so that her head may be supported in drying position and/or released from this position at times, as convenience, comfort and efficiency may dictate.

The arm 8, in the preferred form shown, comprises a bracket member or arm 9 adapted to be secured to the rod 2 by means of a clamp 10 which may be of the type shown secured by butterfly nuts 10' or in any suitable and convenient form.

The bracket 9 will for convenience and clear understanding be specifically described together with other features of the arm 8 in order that it may be clearly understood the details being, however, subject to variation.

The bracket or bracket arm 9 extends upwardly and to the customer's right as shown in Figs. 3 and 4, the object of the incline being to place the clamp 10 below the end or shoulder 2' of the longest fork 4 with which any of the known dryers are equipped thus adapting clamp 10 to engage the rod 2 of any and all of these dryers and maintain pad 7 at the proper location.

The bracket arm 9 is formed at its upper and outer end with a boss 11 having its axis vertical and suitably bored in a vertical direction to receive a sliding and rotary pin 12 which carries formed thereon a sleeve clamp 14 to be described. This boss 12, in the form shown, may be provided with positioning means 15 of a well known type comprising a helical spring 16 held in a radial hole 17 by means of a screw plug 18. The spring 17 bears against a ball 19 which is adapted to engage shallow sockets 20 and 21 in the pin 12, whereby the latter and the sleeve clamp 14 together with the fore and aft arm 22 carried thereby are automatically positioned in on and off or operative and inoperative arrangement. The pin 12 and boss 11 or equivalent means are hereinafter referred to as an articulating connection or joint or an articulatable joint. The bracket arm 9 which is irregularly inclined is preferably of web construction suitable to the shape illustrated and adapted to give sufficient support in the offset relation described.

It is important to note that the bracket arm 9 is so shaped and disposed that the boss 11 is offset backwardly from said bracket arm 9 in relation to the upright 2 as seen in plan Fig. 3.

5 This arrangement as hereinafter more fully described permits the arm 22 to be swung in clockwise direction to a position at right angles to the operative position shown in Fig. 3 whereby it extends outwardly directly to the right of the customer, the latter being thus fully released and enabled to rise freely from the chair.

The clamp 14, as shown in Figs. 3 and 4, is preferably of the split sleeve type the sleeve 14' of such clamp having upper and lower horizontally projecting lips 25 and 26 adapted to be drawn together by a thumb screw 27 to grip the fore and aft arm 22 thereby preventing its sliding from adjusted position in the direction of its length as best illustrated in Fig. 3.

20 It may be noted at this point that the arm 22 is preferably of thin tubular construction to give the desired lightness and to keep the amount of metal consumed to the minimum.

25 The arm 22 as shown is provided with a longitudinally extending key or feather 28 which may be graduated as indicated to determine positions corresponding to different types or makes of dryer apparatus.

30 This key prevents rotation of the arm 22 and consequent displacement of the pad 7 under the weight placed thereupon by the customer and provides for clamping of the said hollow arm 22 preventing rotation and longitudinal sliding without destructive clamping pressure, i. e., pressure which might crush the thin hollow fore and aft arm 22, which is thus permitted to be made of extreme lightness.

35 To co-operate with the key 28 the sleeve clamp 14 is provided at the top with a keyway 29 to receive the key 28 which is likewise at the top.

40 It is of interest to note that in the form of the apparatus shown, according to the preferred proportions in Fig. 3 the bracket arm 9 is so designed that the distance from the center line of upright 45 sliding rod 2 to the center of the arm 22 may be approximately seven inches. Greater spacing involves more metal and heavier parts or greater tendency to failure; less spacing causes the arm to be uncomfortably close to the face and neck, 50 the proportions being variable.

Such proportions and arrangement bring the portion of the fore and aft arm 22 at X in Fig. 3 directly over the shoulder of the customer and hence this portion of the arm must maintain a 55 corresponding elevation.

50 This fore and aft arm 22 is bent at 30 at its forward end being turned toward the customer or to the customer's left to give proper positioning of the pad 7, and at Y as seen in Fig. 3 the arm is bent downwardly being turned to the horizontal and continuing to the customer's left at Z in said figure.

65 This depression of the fore and aft arm 22 at Y and Z provides for proper mounting of the pad 7 beneath the customer's chin, it being customary for the customer to sit with her back to the stand 1, 2 with her head in the dryer 5. The depression of the fore and aft arm 22 at Z provides room for a proper support for the pad 7, underneath the chin while the arm 22 at X clears the shoulder.

70 This pad 7, as shown, comprises a base 31 which to best advantage is hollowed out or dished to receive the sponge rubber or other suitable pad 7. Said base 31 is provided with a central depending portion 32 which, in the form shown, ter-

minates in a pin 33 which is normally vertical and which turns and slides freely in a corresponding hole 34, in the left end of the horizontal portion Z of the fore and aft arm 22.

Horizontal flat surfaces of the arm 22 and of the depending portion or boss 32 of the base 31 meet on a plane indicated by the line 34 in Fig. 4, said plane being horizontal.

Thus the composite arm 8 includes the bracket arm 9 extending to the customer's right (or left if a left handed device is preferred). This arm is preferably offset to place the boss 11 and the pin 12 somewhat to the rear of the upright sliding rod 2 for the purpose stated; i. e., to permit free swinging of the fore and aft arm 22 to the customer's right and substantially to full right angular position. The composite arm 8 includes fore and aft arm 22 and may also include the sleeve clamp 14 mounted on the pin 12 or other suitable mounting for the fore and aft arm 22 which as shown is adapted to be held in said sleeve clamp. This arm is curved to the left and depressed at its forward end at Y, Z, and suitably bored at 33' providing for the support of the pad 7 on a freely sliding and rotating pin 33 in the end of the fore and aft arm 22. The details of the arm 8 and the pad mounting are subject to variation.

It is important that the U-shaped composite arm 8 clear the customer's shoulder and head or neck and support the pad 7 beneath the chin and that the arm be adapted to be clamped at one end in vertically adjustable relation to the vertically sliding rod 2 whereby the pad is moved up and down as the dryer 5 is adjusted to the height of the customer, the pad 7 being maintained at a corresponding height suitable to the support of the head with the scalp in drying relation to the dryer in the concavity of the same. It is also important that the arm 22 swing freely relatively to the bracket or stand to enable the customer to move the pad 7 into and out of cooperative relation to and with the dryer as already pointed out. When released by the unclamping screw 27 the arm 22 can be slid in fore and aft directions to a series of operative positions suitable to different customers and to various makes of dryers such positions being, if desired, designated by the graduations on key 28.

In the adjusted position of the support, the customer's head, the chin being on the pad, is held with the crown or scalp and hair projecting into the dryer which is normally of inverted bowl or downwardly concave shape.

When thus supported the customer is subject to uniform drying action of the hair and with a proper expert adjustment for the right degree of heating, the most satisfactory result is attained in the shortest period of time. The customer is further free to relax and doze without disturbing this relation or in any way changing it and at the same time whenever the customer for any reason desires to be released she can swing the fore and aft arm clockwise and be free to withdraw her head from the dryer. It is also important that the customer is enabled to retain this position indefinitely without effort and without nodding or muscular strain and without danger of cramping. If, for any reason, the position becomes tiresome, the customer may swing the rest aside and change her position until rested and then immediately replace the support without losing the adjustment and resume the same drying position.

I have thus described my invention in the preferred form the description being specific and in

detail in order that the manner of constructing, applying, operating and using the invention may be fully understood, however, the specific terms herein are used descriptively rather than in a limiting sense, the scope of the invention being defined in the claims.

What I claim as new and desire to secure by Letters Patent is:

1. In a hair drying apparatus having a downwardly concave hair dryer adapted to fit over the head; a chin supporting pad beneath the dryer and spaced downwardly therefrom to engage the chin and hold the head with the scalp within and in hair drying relation to the dryer, the pad having a supporting arm, an upright on which the dryer is supported, a bracket and means for securing the bracket to the upright for vertical adjustment along the same, an articulatable joint supported on said bracket and supporting said arm, and having means for guiding said arm on an approximately horizontal path to swing horizontally from adjusted position, permitting the customer in hair drying position to move the pad laterally from beneath the dryer on a predetermined approximately horizontal path thereby releasing herself from the dryer and to swing the arm and pad in the reverse direction to replace the pad beneath the chin supporting the head in the same relation to the dryer.
2. In a hair drying apparatus having a downwardly concave dryer with an upright stand; a chin pad for engaging the chin from beneath and having a supporting arm mounted on and means for securing the same for adjustment vertically along said stand and in relation to the dryer, said mounting comprising an articulatable joint having means for guiding and supporting said arm whereby said arm is swingable laterally on an approximately horizontal path relatively to and beneath the dryer, the pad being adapted by the vertical adjustment to be spaced downwardly from the dryer to engage beneath the chin and support the head with the scalp in the concavity of the dryer and in drying relation thereto and being freely movable by the customer in hair-drying relation to the apparatus to swing to and from said position.
3. In a hair drying apparatus having a downwardly concave hair dryer and a vertically adjustable member on which the dryer is mounted; a chin pad, means whereby the pad is supported on said member in predetermined downwardly spaced relation to the dryer to support the head from beneath the chin with the scalp in the concavity of the dryer, the chin pad being thus adjustable in an approximately vertical direction with the dryer said supporting means further comprising an articulating connection for said arm permitting the chin pad to be moved laterally on a predetermined approximately horizontal path to release the head from the dryer, said lateral motion being obtained by operation of said articulating connection by the customer in hair-drying position, said connections having means supporting the arm and pad approximately on said path.
4. In a hair drying apparatus having a downwardly concave dryer and a vertically adjustable member on which the dryer is mounted, said member being at the back of the customer; a chin supporting pad, a horizontal arm for supporting said pad, said arm having a concavity at one side which in the operative position of the apparatus is toward the customer, a clamp sup-

porting said arm and having means whereby it is engaged to said member and adjusted vertically thereon, means at the other end of the arm for supporting the pad, said clamp having supported thereon an articulating joint which in turn supports the arm providing for a free lateral swinging motion of the arm and pad on a predetermined path, said swinging motion being actuated by the customer in hair-drying position for locating the pad beneath the dryer to support the head in drying relation thereto whereby said pad may be engaged beneath the customer's chin and released from this position by the customer and returned by her to supporting position without vertical readjustment.

5. A chin support for attachment to a dryer stand to support the head in drying relation to the dryer, the same comprising a bracket mounted for vertical adjustment on the stand, an approximately horizontal arm and means whereby said arm is supported on the bracket for adjustment in fore and aft directions, said fore and aft arm having a relatively depressed lateral inward extension at its forward end and a chin supporting pad removably mounted on said lateral extension said supporting means comprising an articulating joint permitting the dryer to be freely withdrawn from supporting position to release the head, said articulating joint being adapted to confine the chin pad to a predetermined approximately horizontal path at and adjacent its supporting position.

6. A chin support for attachment to a dryer stand to support the head in drying relation to

the dryer, the same comprising a bracket mounted for vertical adjustment on the stand, a fore and aft arm, means whereby said arm is mounted on the bracket for adjustment in the direction of its length, said fore and aft arm having a relatively depressed lateral extension at its forward end and a chin supporting pad removably mounted at the end of said lateral extension, said fore and aft arm having an articulating joint comprising guiding means whereby it is mounted to swing freely on a predetermined path which is approximately horizontal at and adjacent the supporting position of the pad to move said pad into and out of vertical alignment with a dryer on said stand.

10 7. A chin support for attachment to a hair-dryer stand to hold the head in drying relation to the dryer the same comprising a bracket, means whereby said bracket is mounted for vertical adjustment on the dryer stand and a fore and aft arm having a relatively depressed lateral extension at its forward end; a chin supporting pad mounted on said lateral extension and an articulating joint for supporting said fore and aft arm on said bracket for pivotal motion about an upright axis to and from chin supporting position and for translatory motion in a direction of the length of the arm, said arm support having means for preventing rotation of the arm about its long axis and friction means permitting but controlling said pivotal motion which is conveniently operable by the customer in hair-drying position.

GERTRUDE M. HIGGINS.
